RAIL BRAKE

Carl W. Smith, Glendale, Calif., assignor to The Westinghouse Air Brake Company, Wilmerding, Pa., a corporation of Pennsylvania

Application January 28, 1937, Serial No. 122,753

7 Claims. (Cl. 188—165)

This invention relates to rail brakes for vehicles, such as railway trains, and the principal object of the invention is to guard against and prevent injury to the rail brake shoes, as well as to the associated mounting and lifting mechanism, caused by the failure of the brake shoe to over-ride obstructions in the line of travel of the shoe while sliding along the rail in contact therewith.

10 The usual type of rail brake shoe has a bevel at the opposite ends thereof which inclines upwardly from the rails to assist in enabling the rail shoe to over-ride irregularities in the level of the rails, as at the joints between successive rail sections.

15 I have found, however, that the usual bevel on the end of the rail shoes is ineffective to enable the shoe to over-ride a switch frog or point which may project above the level of the rails of the main track. A particular instance is known of a rail shoe, having the usual bevel at the ends thereof, which caught on a projecting switch frog or point in endeavoring to follow the wheel trucks passing from the main track to a side track divergent from the main track at the switch and failed to over-ride the projecting switch frog. Serious physical damage to the rail shoe itself, as well as to the mounting and lifting mechanism for the rail shoe, resulted. The car having the rail shoe was consequently put out of service for the length of time required to repair the damage, which, in the instance known, was several weeks due to the difficulty in securing replacement parts.

20 My invention is accordingly designed to prevent the occurrence of such damage to the rail brake shoe and its mounting and lifting mechanism, as well as the attendant loss of time that the car is out of service while the damages are being repaired. The invention comprises the provision of what I have designated as "skid blocks" or curved "nose" members which are suitably formed or secured at each of the four corners of the rail brake shoe, which skid blocks are especially designed to enable the rail shoe 25 to ride up over obstructions in the path of the shoe, such as a projecting switch frog or point.

25 My invention will be described in detail hereinafter in connection with the accompanying drawings, wherein,

30 Fig. 1 is a fragmentary elevational view, showing a magnetic rail brake shoe assembly embodying my invention.

35 Fig. 2 is a sectional view taken on the line 2—2 of Fig. 1 showing in further detail the rail brake 40 shoe assembly.

45 The pole pieces 15 are provided at the opposite ends thereof with the usual bevel 18 for assisting in enabling the rail shoes to slide over uneven rail 50

5 Fig. 3 is a diagrammatic view of a railroad track and a switch frog, with rail brake shoes, not embodying my invention, so positioned as to illustrate the manner in which the rail brake shoes may strike the switch frog and be laterally diverted.

10 Fig. 4 is a fragmentary sectional view, taken on the line 4—4 of Fig. 3, further illustrating how the rail brake shoes may strike the switch frog or point and be laterally diverted.

15 Fig. 5 is a fragmentary elevational view, showing one end of a rail brake shoe embodying my invention.

20 Figs. 6 and 7 are perspective views of two detachably constituted skid blocks in their relative 15 positions as secured to one end of a rail brake shoe, and

25 Fig. 8 is a fragmentary sectional view corresponding to the view in Fig. 4 and showing in further detail the manner in which the skid blocks comprising my invention are secured to the track shoes, as well as the manner in which the skid blocks are effective to permit the track shoe to ride over obstructions on the rail, such as the raised edge of a switch frog or point.

30 As shown in Fig. 1 of the drawings, the rail brake shoe assembly may comprise a rail brake shoe 11 suitably mounted on a wheel-truck having side frames 12, only one of which is shown, and front and rear wheels 13 which roll along a track rail 19.

35 The rail brake shoe 11 may be of the magnetic type and may comprise a suitable magnetic core structure having two spaced, laminated side portions 14 to which are respectively secured two spaced oppositely disposed pole pieces 15 of suitable magnetic material such as cast iron. A suitable filler or spacer 16 of non-magnetic material is interposed between the opposite pole pieces 15 to prevent the entrance of dust or dirt particles between the pole pieces 15.

40 A plurality of electromagnet coils 17, only one of which is shown in Fig. 2, are mounted between the side portions 14 of the magnetic core structure, the coils 17 having a central axial core extending therethrough from one side portion 14 to the opposite side portion 14.

45 As will be noted in Figs. 1 and 2, the rail shoe 11 is normally suspended in vertical alignment with the rail 19, the pole pieces 15 extending longitudinally of the rails and adapted to slidably contact the rail when the shoe is sufficiently lowered from its normal position.

50 The pole pieces 15 are provided at the opposite ends thereof with the usual bevel 18 for assisting in enabling the rail shoes to slide over uneven rail 55

joints and other similar irregularities in the rails, while the shoe is in sliding contact with the rail.

5 A guide stirrup or member 21 for each end of the rail shoe 11 is provided, the members 21 being suitably attached to the side frame 12 of the wheel truck. The upper portion of the rail shoe 11 extends between opposite guiding faces of the guide member 21, the width of the rail shoe being less than the distance between the guide faces in order to enable a limited lateral rocking movement of the rail shoe whereby the shoe may adjust itself to irregularities in the surface of the flange of the rail and maintain maximum area of contact therewith.

10 The rail shoe 11 is lowered into contact with the track rail 19 and raised out of contact therefrom by suitable means, such as the two lifting cylinders 23 shown, which are attached or 15 mounted, as by mounting lugs 24, to transverse struts or members 25 which extend between the side frames 12 at opposite sides of the wheel truck. When fluid under pressure is supplied to each of the cylinders 23, as through a supply 20 pipe 26, a piston (not shown) within the cylinders is shifted upwardly and causes a corresponding shifting of a stem or rod 27. One end of the rail shoe 11 is pivotally suspended by a pair of links or struts 28 from the uppermost end of the 25 stem 21 of one lifting cylinder 23 and the opposite end of the shoe is similarly supported or suspended by a pair of links 28 from the uppermost end of the stem of the other cylinder. The links 28 are pivotally connected to brackets 29 30 attached to the rail shoe 11. The pivotal connection of the links 28 to the stem 27 and to the brackets 29 is effected by means of bolts and nuts 31 and springs 32, which serve to prevent chattering and also to permit a flexible connection 35 between the rail shoe and the lifting cylinders 40 so that the shoe may adjust itself to irregularities in the surface of the rail flange.

With fluid under pressure supplied through the pipe 26 to the cylinders 23, the stems 27 are 45 held in a raised position so that the rail shoe is accordingly held in a raised position out of contact with the track rails. When fluid under pressure is released from the cylinders 23, the rail shoe falls, due to its own weight, into contact 50 with the track rail. Current is supplied to the electromagnet coils 17 and energization thereof effected in any suitable manner to effect the magnetic attraction between the rail shoe and the track rail.

55 In Figs. 3 and 4 there is shown a switch frog 35 for switching vehicles from the main line track rails, designated as rails 19a, to side track rails, designated as rails 19b. If as is frequently the case, the main track rails settle or the wear on 60 the flange of the main track rails 19a greatly exceeds the wear on the flanges of the side track rails 19b, due to the higher proportion of traffic on the main track rails as compared to the traffic on the side track rails, the member 19c of the 65 switch frog which is moved into contact with the main track rail 19a will eventually project above the top surface of the flange of the main track rails 19a.

In such case, with the switch frog 35 in the 70 position shown in Figs. 3 and 4 wherein it causes the traffic moving in the direction of the arrow, that is in the right-hand direction as viewed in Fig. 3, to switch from the main track rails 19a to the side track rails 19b, and with the rail 75 shoe lowered into sliding contact with the rails,

the lower edge of the pole pieces 15 on the rail shoe at one side of the wheel truck will strike the raised edge of the member 19c of the switch frog 35. As will be best seen in Fig. 4, the side edge of the pole pieces 15 of the usual rail brake 5 shoe is perpendicular to the surface of the rail flange and thus the rail shoe will be diverted laterally along the edge of the member 19c of the switch frog in the direction of the main track rails 19a without being able to ride up and over 10 the projecting edge of the member 19c.

I have found that even though the angle of inclination with respect to the track rails of the usual bevel 18 at the end of the rail shoes is decreased from the usual angle and even though 15 the side edges of the usual bevel are rounded off, the rail brake shoe cannot ride up and over the projecting edge of the member 19c, if the member 19c of the switch frog projects an appreciable distance above the top flange of the main track 20 rail 19a.

According to my invention, I have accordingly provided specially devised "skid blocks" 38, shown in detail in Figs. 6 and 7 which may be applied to existing rail shoes of the usual type to convert 25 them into shoes capable of riding over the raised edge of a member of a switch frog and thereby to prevent severe damage to the rail brake equipment.

It will be understood that while my invention 30 is illustrated in a form particularly applicable to the conversion of existing rail brake shoes, it may readily be applied in principle in the initial manufacture of the rail shoes.

As will be clearly apparent in Figs. 1 and 2 of 35 the drawings, the skid blocks are relatively short in length compared to the total length of the rail brake shoes, a skid block being attached to the pole pieces 15 of the rail brake shoe in the angle between the horizontal and vertical portions of 40 the pole pieces 15, at the four corners of the rail brake shoe.

In order to provide proper seating for the skid blocks 38, the horizontal portions of the pole pieces 15 are provided with suitable recesses 41 45 (see Figs. 1 and 5) for receiving therein a corresponding projection 42 formed on one face of the skid block. Suitable screws 40 cooperating with threaded bores 43 in the skid block and in the pole pieces 15 serve to secure the skid blocks 50 38 to the pole pieces 15.

As will be clearly apparent in Figs. 7 and 8, the side surface 50 of the skid block 38 extends laterally outward and upwardly from the rail-contacting surface of the vertical portions of the 55 pole pieces 15, the side surface curving inwardly toward the track rail at the opposite ends of the block 38. While the side surfaces 50 are illustrated as substantially straight, they may be curved if desired. The ends of the skid block 33 60 are cut away or inclined to merge into and to conform to the angle of inclination of the bevel 18 at the end of the rail brake shoe.

The inner edge of the skid block 38, as well as the inner edge of the projection 42 on the skid block, is beveled in order to insure proper fitting of the skid block in the angle between the horizontal and vertical portions of the pole pieces 15, which might be prevented by irregularities of the fillet on the pole pieces.

70 Referring to Fig. 8, the manner in which the skid block 38 functions will be readily understood. The inwardly curved nose or end of the skid block 38 which merges into the bevel 18 at the end of the rail shoe 11 will strike the 75

projecting or raised edge of the member 19c of the switch frog 35 and, acting as a wedge, will tend to raise the rail brake shoe, against the magnetic force of attraction tending to hold 5 the rail shoe in contact with the rail. Should the rail brake shoe tend to be diverted laterally by the raised edge of the member 19c, the side surface of the member 19c, acting as a wedge, will cause the rail shoe to be raised so as to 10 slide over the projecting edge of the member 19c. Accordingly, the rail brake shoes will follow the car wheels, indicated by broken lines in Fig. 3, in the direction of the side track rails 19b instead of being diverted along the main 15 track rails 19a.

While I have illustrated and described only one embodiment of my invention, it will be understood that various modifications, omissions or additions may be made with respect to the 20 embodiment of my invention shown, without departing from the spirit of my invention. It is accordingly not my intention to limit the scope of my invention except as it is necessitated by the scope of the prior art and otherwise than 25 as defined in the appended claims.

Having now described my invention, what I claim as new and desire to secure by Letters Patent, is:

1. A rail brake shoe for a vehicle, comprising 30 a rail-contacting member, and means on said member having a forwardly inclined surface curved laterally outward from the end of the member and a surface extending longitudinally for a portion of the length of the shoe as well 35 as laterally outward and upwardly from the rail-contact surface of the rail-contacting member, into which the said curved surface merges.

2. A rail brake shoe for a vehicle, comprising 40 a rail-contacting member which extends longitudinally of the rails and is of substantially rectangular shape, and means at each of the four corners of said member having a forwardly inclined surface curved laterally outward from the end of said member and a surface extending 45 longitudinally for a portion of the length of the shoe as well as laterally outward and upwardly from the rail-contact surface of the rail-contacting member, into which the said curved surface merges.

3. A rail brake shoe for a vehicle, comprising 50 a rail-contacting member adapted to be disposed perpendicularly of the rail in alignment therewith, and means on opposite sides of the rail-contacting member at one end thereof having a side surface which extends laterally outward and upwardly from the rail-contact surface of the rail-contacting member, which side surface curves laterally inward adjacent the end of the shoe toward the rail-contacting member, the 55

said surfaces on said means enabling the brake shoe to over-ride obstructions in the line of travel of the shoe when the shoe is in contact with the rail.

4. A rail brake shoe for a vehicle, comprising 5 a rail-contacting member adapted to be disposed perpendicularly to the rail in alignment therewith, and two detachable members secured respectively on opposite sides of said rail-contacting member adjacent the end thereof, each of 10 said detachable members having a side surface extending laterally outward and upwardly from the rail-contact surface of the rail-contacting member and curved laterally inward at the end of the shoe toward the rail-contacting member, 15 the surfaces on said detachable members enabling the brake shoe to over-ride obstructions in the line of travel of the shoe when the shoe is in contact with the rail.

5. Protective means for preventing injury to 20 vehicle rail brake shoes, which injury would otherwise occur due to the brake shoe striking obstructions in the path of the shoe when lowered to the rail and failing to over-ride such obstructions, comprising means at opposite sides 25 of the brake shoe at one end thereof providing a surface which extends for a portion of the length of the shoe laterally outward and upwardly from the rail-contact surface of the brake shoe and which curves laterally inward 30 adjacent the end of the brake shoe.

6. Protective means for preventing injury to 35 vehicle rail brake shoes, which injury would otherwise occur due to failure of the brake shoe to over-ride obstructions in the path of the shoe 40 when lowered to the rail, comprising means at opposite sides of the brake shoe and at each end thereof providing a surface which extends laterally outward and upwardly from the rail-contact surface of the brake shoe and which curves laterally inward adjacent the corresponding end of the shoe.

7. A rail brake shoe for a vehicle, comprising 45 a rail-contacting member adapted to be disposed perpendicularly to and in alignment with the track rail and having surfaces at opposite ends thereof inclined forwardly relative to the surface of the rail, and means on one side of the rail-contacting member adjacent one end of the shoe providing a surface which extends for a 50 portion of the length of the shoe laterally outward and upwardly from the rail-contact surface of the rail-contacting member and which curves laterally inward at the end thereof adjacent the end of the brake shoe toward the rail-contacting member, the curved portion of said surface merging into the forwardly inclined surface at the end of the rail-contacting member. 55

CARL W. SMITH.
